UNITED STATES PATENT OFFICE

1,970,267

LOCKER

James E. Bales, Aurora, Ill., assignor to Lyon Metal Products, Incorporated, Aurora, Ill., a corporation of Illinois

Application May 8, 1930, Serial No. 450,642

26 Claims. (Cl. 312—106)

This invention relates to lockers and particularly to lockers which are made of sheet metal. More specifically, the invention relates to locker door construction and to locker door reinforcing means and locking mechanisms.

The primary object of the invention is to provide a sheet metal locker which is provided with new and novel means for reinforcing the locker door, which is provided with improved means for housing a locking bar or rod, and which is provided with novel means for locking the door.

Another object is to provide a locker door reinforcement and a hinge reinforcement for the door.

5 A further object is to provide a new and improved locking mechanism for sheet metal lockers.

A further object is to provide a door locking mechanism of novel construction which is manually operated for unlocking and which automatically comes to locking position upon closing the door.

Another object is to provide a reinforced locker which is strong and durable in construction, which is efficient in operation, and which can be readily and economically manufactured.

A still further object is to provide a new and improved method of slidably arranging a locking bar or rod in position.

Numerous other objects and advantages will be apparent throughout the progress of the following specification.

The invention comprises in general a sheet metal locker of conventional design which has doors made from sheet metal. The doors are preferably made out of a sheet metal blank and are provided with extensions on each side which are folded back and overlapped to provide longitudinal side reinforcements and to provide a housing into which a vertical locking bar or rod is arranged.

Hinge reinforcing members or braces are fastened to a longitudinal reinforcement at the hinge side thereof to strengthen the door where it is hinged to the locker or cabinet body. The side reinforcing at the free side of the door is formed to provide a longitudinal recess into which a locking rod or bar is slidably mounted. This rod or bar is rectangular and hollow in shape and has a longitudinal recess or slot extending its full length. Notches are cut therefrom which engage

50 rod clips fastened to the inside of the door. The rod or bar interfittingly or interlockingly engages these clips to hold the rod in position and to permit vertical slidable movement thereof. A plate is fixed to the rod and is movable therewith.

55 It is adapted to engage a lock fixed to the inside

of the door and operated by keys from outside the door. When the lock is in locked position, the bolt engages the plate to prevent movement of the rod. When the lock is in unlocked position, the bolt is withdrawn and the rod is free to be slid vertically. An outside handle is fixed to the door and has a vertical slideable member cooperating therewith which engages the rod. This slideable member is provided for operating the vertical bar from the outside. The slideable member also has a hole provided in its lower end to receive a padlock so that the rod cannot be slid even though the regular door lock is in unlocked position. A door stop and keeper element is fixed to the jamb and engages a longitudinal slot in the rod for locking the rod to the locker body. A leaf spring member is fastened to a part of the door and extends inside of the rod. Parts are struck-out from the rod which are engageable with the spring to hold the rod in up or unlocked position when the door is opened. This spring is engaged by the stop or keeper when the door is closed to move the spring away from the struck-out portions, thereby permitting the bar to slide downwardly by gravity and engage the stop or keeper.

The accompanying drawings illustrate a selected embodiment of the invention and the views therein are as follows:

Fig. 1 is a detail perspective view of the improved locker embodying the invention.

85

Fig. 2 is a similar view showing the locker door in open position and hinged on the left side of the locker.

Fig. 3 is a detail transverse sectional view on the line 3—3 of Fig. 1, except the door is hinged on the left side instead of the right side as shown in Fig. 1.

Fig. 4 is a longitudinal vertical sectional view on the line 4—4 of Fig. 6 showing the door in closed position with the rod in locked position.

90

Fig. 5 is a similar view showing the rod in raised or unlocked position.

Fig. 6 is a detail elevation of the door looking at the inside thereof.

Fig. 7 is a detail perspective view of a part of the door with the locking rod out of engagement therewith.

Fig. 8 is a detail perspective view of the hinge brace.

Fig. 9 is a detail plan view of the blank from which the hinge brace is made.

Fig. 10 is a detail vertical sectional view on the line 10—10 of Fig. 6.

Fig. 11 is a detail sectional view on the line 11—11 of Fig. 6.

110

Referring to the drawings, 1 designates a locker generally having side jambs 2 and 3. A sheet metal door 4 is swingingly mounted to the jamb 2 by means of hinges 5. The side edge 6 of the door is bent inwardly at 7 and then folded back upon itself to provide two thicknesses of metal 8 and 9. The side 9 extends along the inside face of the door as designated at 10 and then bent outwardly between the portion 10 and its free end 11 to provide a tubular portion 12, Fig. 3. The tubular portion 12 comprises the sides 13 and 14 and integrally joins the part 11 as designated at 15. The portion 10 and the end 11 may be fastened to the face of the door in any convenient manner such as by welding. The side 14 of the tubular member 12 has a lip 16 struck inwardly therefrom to provide a slot 17.

A hinge brace 18 is formed from a sheet metal blank as shown in Fig. 9. This blank is folded 20 along the dotted lines shown in Fig. 9 and when so folded, forms the brace as shown in Fig. 8. The brace 18, Fig. 8, comprises an integral finger 19 which has a turned end 20. The base portion 21 of the brace 18 is integral with the finger 19 25 and the reinforcing sides 22. The base 21, Fig. 3, abuts the inside of the metal where it is folded at the side of the door and is shaped to conform with the tubular portion 12 which reinforces the door. The turned end 20 of the finger 19, Fig. 3, 30 is received in the slot 17 and engages the metal at the edge of the slot. Fastening means 23 which, in this instance comprise a bolt and nut, passes through holes 24 provided in the base 21 of the brace, the folded edge 6 of the door which 35 comprises the parts 8 and 9, and a leaf 25 of the hinge 5. The other leaf 26 of the hinge 5 is fastened to the angle iron jamb 2 in any convenient manner such as by rivets 26'.

The extension on the other side of the door 40 which is that part adjacent the jamb 3, is bent inwardly and then returned to provide the reinforced side edge 27. The metal is then bent downwardly to provide a side 28 which is fastened to the inside face of the door and then bent 45 inwardly to provide the vertical face 29. The space between the reinforced edge 27, the front face 28, and the vertical edge 29 provides a longitudinal recess 30 for a purpose which will hereinafter appear. The free end of the metal is 50 then bent laterally at 31 and then downwardly to provide a leg 32 which is fastened to the inside face of the door in any convenient manner such as by welding.

Door rod clips 33 are fastened to the inside 55 face of the door, extending inwardly from the front face 28, Fig. 6. The clips 33 are formed from sheet metal and comprise upper and lower portions 34 and 35 and an intermediate portion 36. The upper and lower portions 34 and 35 are 60 fastened to the inside face 28 in any convenient manner such as by welding. The portion 36 is bowed outwardly from the portions 34 and 35 and is connected by the thin strip portions 37 and 38 respectively.

65 A locking rod or bar 39 is made tubular in form from a single piece of sheet metal. The rear side 40 of the rod has its free ends 41 and 42 spaced apart, Fig. 7, to provide a longitudinal recess or slot 43. At spaced intervals the ends 41 and 42 70 are cut away at 44 and 45 respectively to provide notches 46. The rod is positioned in the recess 30 with its surface 40 against the side 28. The intermediate portions 36 of the clips 33 are received in the notches 46 in the rod, thereby permitting vertical movement of the rod as the con-

nnecting strips 37 and 38 fit into the longitudinal recess 43. The front face 47 of the locking rod or bar 39 is provided with a longitudinal slot 48, Fig. 2, into which a part of a keeper element 49 extends.

The element 49 comprises a leg 50 which is fastened to the angle iron jamb 3 of the locker by means of rivets, Fig. 3. A rearwardly extending leg 51 is integrally connected with the leg 50. The leg 51 is bent at right angles providing an inwardly extending arm or leg 52. This arm or leg 52 is bent forwardly to provide a keeper portion 53. This keeper portion is cut away from the arm 52 as designated at 54, Fig. 10, and has a spaced lug or lip 55 providing a recess or keeper 56 into which the metal of the rod 39 adjacent the slot 48 is received for locking the locker door. A felt bumper 57 is fastened to the outer face of the leg 52 against which the edge 27 of the door abuts when it is closed and acts as a stop for the door, Fig. 3.

A handle 58 is preferably made from a single piece of sheet metal and is curled or beaded-over as clearly shown in Figs. 3 and 11, to provide a slotted or grooved portion 59. The upper edge 1 of the handle has a right angled lip 60 provided thereon which engages a slot provided in the face of the door to hold the upper end of the handle in position. The lower end of the handle has a downturned flange or lip 61 provided 1 thereon which fits flush with the face of the door and is held in place by means of the fastening bolt and nut, Fig. 11. A slidible member 62 is arranged inside the upper and lower limits of the handle 58 and has forwardly extending ends 63 1 and 64 which operate in the groove portion 59 of the handle. The slidible member has a projection 65 provided thereon upon which outwardly extending fingers 66 are integrally formed. The projection and fingers extend through a 1 slot provided in the face of the door, and the fingers 66 extend through a slot 67 provided in an attaching plate 68. After the fingers are inserted in the slot 67, they are spread apart to connect the slidible member securely to the plate 68. 1 The slidible member also has a projection 69 provided at its lower end, Fig. 11, which extends through a slot 70 provided in the bottom of the handle 58. The construction just described permits the slidible member 62 to be raised 1 upwardly to raise the sliding rod or bar 39. The extension 69 provided on the slidible member 62 has a hole 71 provided therein to receive a padlock 72, Fig. 1. When the padlock is fastened in position, the vertical member cannot be moved 1 as a part of the lock will engage the bottom of the handle 58 and prevent movement thereof.

The plate 68 is attached to the rod 39 as indicated at 73 and extends inwardly from the rod. The inner end 74 of the plate is provided 1 with a turned flange 75 which is adapted to be engaged by the draw bolt 76 of a key operated lock 77. The upper edge of the flange 75 is cut away as indicated at 78, Fig. 6, to permit the bolt 76 to pass over the face of the plate 68 and 1 become engaged with the part 75 when the lock 77 is in locked position so that the rod 39 cannot be operated.

A leaf spring 79, Fig. 10, is fastened to a fixed part of the door, such as to a clip 33, and normally extends in the position shown in dotted lines in Fig. 10. A lug 80 extends inwardly from the rod 39. This lug may be either struck-out from a face of the rod or it may be an integral part of a clip 81. If the clip 81 is employed, 1

another lug 82 is provided on the clip, the lugs 80 and 82 being bent inwardly to prevent it from falling out of the rod 39. The spring when in the position shown in dotted lines, Fig. 10, engages the bottom of the lug 80 and holds the tubular rod 39 upwardly. When the door is closed, the finger 55 on the keeper element 49 will push the leaf spring 79 to the position shown in full lines in Fig. 10, and permit the rod to drop by gravity until it engages the keeper 56. When the lock 77 is in locked position, the bolt will engage the flange 75 on the plate 68 thereby preventing vertical movement of the slidable rod.

Operation

When the door is pushed to closed position, the part 53 of the keeper element 49 will extend through the slot 48 in the tubular rod 39 and push the leaf spring 79 to the left, Figs. 4, 5, and 10, pushing the end of the spring 79 away from the lug 80. The tubular rod 39 will then drop downwardly by gravity until the metal at the top of the slot 48 engages the keeper 56. The door will then be in locked position as shown in Fig. 4. When in locked position, the slidable member 62 will be down as shown in Fig. 4 with the projection 69 extending below the bottom of the handle 58. If the padlock 72 is engaged with the hole 71 in the slidable member 62, the rod 39 cannot be raised upwardly to disengage the rod from the keeper. Or, if the lock 77 is in locked position with the bolt extending outwardly as shown in Fig. 6, the rod cannot be moved upwardly as the flange 75 will engage the draw bolt 76.

To unlock the door either the padlock 72 must be removed, or the lock 77 unlocked to withdraw the draw bolt 76. In this latter position, the slidable member may be moved upwardly to disengage the tubular rod 39 from its keeper 56. When the rod is raised upwardly a predetermined distance due to raising the slidable member 62, the leaf spring 79 will engage the lug 80 and hold the tubular rod 39 in up or unlocked position as shown in Fig. 5. The door may then be swung on its hinges 5. When the door is closed, the finger 53 will push the spring inwardly permitting the slidable member 62 and the rod 39 to drop downwardly into engagement. The lock 77 or the padlock 72 may then be used to prevent vertical movement of the slidable member and thereby maintain the door in locked position relative to the locker.

The slidable member 62 is guided by means of the upper and lower tongues or projections 63 and 64 entering the groove in the handle 58. The projection or tail-piece 69 on the slidable member 62 is not required as a guide for the slidable member to maintain it in position, the tail-piece 69 being provided merely for receiving a padlock.

Upper and lower bumpers 83 and 84 respectively are arranged in the handle 58 to provide a surface against which the slidable member 62 strikes. These bumpers are made of resilient material, such as rubber, and are preferably made T-shaped. The head 85 of the T being inserted in the hollow handle with the leg 86 of the T projecting through the handle and providing a strike for the slidable member 62. The material from which the bumpers are made may be a long strip of rubber material which is T-shaped in cross section. This strip may be cut in required lengths to provide the bumpers which are inserted in the hollow handle with the leg 86 extending outwardly from the handle. This construction is more

economical than fixing a rubber bumper to the top and bottom of the slidable member. The rubber bumpers are impinged within the hollow handle and are always located in proper position relative to the slidable member 62.

The invention provides a locker which has its door reinforced at each side thereof and which provides a recess or pocket into which the tubular slidable member operates. The tubular locking rod is formed from a single piece of sheet metal and has vertical slidable movement due to the interlocking of the rod with the clips. The rod may be operated from the outside due to the slidable member having restricted movement within the handle. Operation of the slidable member or the tubular rod is prevented by either a door lock or a padlock. The leaf spring holds the tubular rod 39 in up position when the door is open and automatically permits the rod to drop down by gravity when the door is closed. The entire locker can be readily and economically manufactured as it is composed of comparatively few and simple parts most of which have interlocking engagement with other parts thereby preventing the use of numerous screws, bolts, and rivets.

The clips 33, by engaging the notches and longitudinal slot in the hollow locking bar, conceal all the means for attaching the bar to the door. The construction of the door, by providing the recess 30 which is arranged between the jamb 27 and the tubular reinforcement 31, provides means for receiving the locking bar, said means being closed on three sides. When the bar is arranged inside of the recess 30, the front face of the locking bar is either flush with the outer face of the flange 27 and the tubular reinforcement 31, or else it may extend inwardly. By providing a member which is closed on three sides for receiving a bar, all the fastening means for holding the bar 31 are concealed and the locking bar is located in a position where it will not come into contact with any of the other operating parts or be easily damaged by coming in contact with outside objects.

The bracket construction for providing a reinforcement at the hinges considerably strengthens the door at this point.

Changes may be made in the form, construction, and arrangement of the various parts without departing from the spirit of the invention or sacrificing any of its advantages, and the right is hereby reserved to make all such changes as fairly fall within the scope of the following claims.

The invention is hereby claimed as follows:

1. A sheet metal locker comprising side jambs, a sheet metal door between said jambs and having integral side extensions, said extensions being bent to provide a flange of double thickness at each side of the door, longitudinal tubular reinforcements on one face of the door and integral with the extensions, said tubular reinforcements being spaced from the flanges at the sides of the door, hinges on one side of the door and fastened to a jamb, and a hinge reinforcing member engaging one of said tubular reinforcements and fastened to an adjacent side flange.

2. A sheet metal locker comprising side jambs, a sheet metal door between said jambs and having integral side extensions, said extensions being bent to provide a flange of double thickness at each side of the door, longitudinal tubular reinforcements on one face of the door and integral with the extensions, said tubular reinforce-

ments being spaced from the flanges at the sides of the door, hinges on one side of the door and a said jamb for swingingly mounting the door, a sheet metal hinge reinforcing member fastened 5 to one of said flanges, and a turned lip on said hinge reinforcing member and engaging one of said tubular reinforcements to strengthen the door when a hinge is applied.

3. A sheet metal locker comprising side jambs, 10 a sheet metal door between said jambs and having integral side extensions, said extensions being bent to provide a flange of double thickness at each side of the door, longitudinal tubular reinforcements on one face of the door and integral with the extensions, said tubular reinforcements being spaced from the flanges at the sides of the door, a hinge having a pair of legs for swingingly mounting said door to a jamb, one of said legs being fastened to one of said jambs, 15 20 the other hinge leg engaging an outer face of a flange, a sheet metal hinge reinforcing member engaging an inner face of the last named flange, a turned lip on said reinforcing member and engaging one of said tubular reinforcements, and 25 fastening means passing through a part of said hinge reinforcing member, said last named door flange, and the last named hinge leg.

4. A sheet metal locker comprising side jambs, 30 a sheet metal door between said jambs and having integral side extensions, said extensions being bent to provide a flange of double thickness at each side of the door, longitudinal tubular reinforcements on one face of the door and integral with the extensions, said tubular reinforcements being spaced from the flanges at the sides of the door, hinges on one side of the door and a jamb, a sheet metal hinge reinforcing member fastened to one of said flanges, a turned lip on said hinge reinforcing member and engaging one of 35 40 said tubular reinforcements to strengthen the door when a hinge is applied, a tubular locking rod arranged in a space between a flange and a tubular member, means for slidably mounting the rod in said space, and means on a jamb and 45 engaging the rod for locking the door.

5. A sheet metal locker comprising door jambs, a sheet metal door between said jambs and hinged to one of said jambs, an integral extension on said door, said extension being folded 50 over to provide an inwardly extending door flange, a leg on said flange and arranged against the inside face of the door, an integral extension on said leg and providing a space between the flange and the last named integral extension, an inward extension on said last named extension and 55 providing a longitudinal reinforcement for the door, a tubular sheet metal locking rod arranged in the space between the flange and the extension on the leg, means on said leg and engaging said 60 rod for slidably mounting said rod on the door, and means on the jamb and cooperating with the rod for locking the door.

6. A locker comprising door jambs, a door arranged between said jambs and swingingly connected to a jamb, clips fixed to a rear face of 65 said door, said clips having their ends fastened to the inside face of the door and bowed between their ends, a relatively wide intermediate portion between the ends of said clips for attaching 70 the clips, relatively narrow strips connecting the ends with the intermediate portion, a locking rod having a longitudinal slot and notches, said slot extending throughout the entire length of the rod, said notches receiving the intermediate 75 portion whereby the rod is free to slide verti-

cally, the slot in the rod engaging the strips on said clips and the intermediate portion being within the rod, and means on a jamb and adapted for engagement with the rod for locking the door.

7. In a locker, a door therefor, a hollow sheet metal locking rod removably and slidably connected to the inside of the door, a hollow handle connected to the front of said door, said handle having a slot therein, a slideable member operably connected to said rod for operating said rod, a lip on the slideable member and extending through the slot into the inside of the handle to guide the slideable member, and locking means engageable with the slideable member for preventing movement thereof.

8. In a locker, a door therefor, a hollow sheet metal locking rod removably and slidably connected to the inside of the door, a handle connected to the front of said door, a plate on said rod, a slideable member on the front of the door and engaging the plate for operating the rod, an extension on the slideable member and extending through the handle, and adapted to be engaged with a padlock for preventing operation 1 of the slideable member.

9. In a locker, a door therefor, a hollow sheet metal locking rod removably and slidably connected to the inside of the door, a handle connected to the front of said door, a plate on said 1 rod, a slideable member on the front of the door and engaging the plate for operating the rod, an extension on the slideable member and extending through the handle, and a key controlled lock fastened to the inside of the door and controlled 1 from the outside thereof and engageable with the plate for preventing operation of the rod.

10. A locker comprising door jambs, a door mounted between the jambs, a hollow slideable locking rod mounted on the door for preventing 1 or permitting opening and closing of the door, a spring fastened to a part of said door and extending into said rod, a lug on said rod and engageable with the spring for holding the rod in unlocked position when the door is open, and a keeper element fixed to a jamb and engaging the spring to disengage it from the lug and to permit the rod to drop by gravity to locked position when the door is closed.

11. A locker comprising door jambs, a door arranged between the jambs and pivotally attached to a jamb, a slideably mounted locking rod on the door for preventing or permitting opening and closing of the door, a spring fastened to a part of said door and extending into said rod, a lug on said rod and engageable with the spring for holding the rod in unlocked position when the door is open, said rod having an opening 12 therein opposite said spring, a keeper element on a jamb and having a part extending into said opening in the closed position of the door for disengaging the spring from the lug to permit the rod to drop by gravity to locked position during closing of the door.

12. A locker comprising a door jamb member, a door member pivotally attached to said jamb member, a slideable locking rod mounted inside of the locker and upon one of said members, the other of said members having a keeper, said locking rod and keeper preventing or permitting opening and closing of the door, a spring fastened to a part of said door and extending into said rod, a lug on said rod and engageable with the spring for holding the rod in unlocked position when the door is open, said rod having 15

- an opening therein opposite said spring, a part of said keeper extending into said last named opening when the door is in closed position for disengaging the spring from the lug to permit 5 the rod to drop by gravity to locking position during closing of the door, and locking means for preventing movement of said rod. 13. A locker comprising door jambs, a locker door arranged between jambs, hinges connecting 10 the door and a jamb, a sheet metal hinge brace having one end fixed to the door where the hinge is attached and having a finger engaging a slot in a part of the door for reinforcing the door at the hinges. 14. A locker comprising a door, a locking rod for locking the door in closed position, a handle on the front of said door, a slidable member on the door and engaging the rod for operating said rod, and horizontal extensions on said slidable 20 member and engaging the handle for guiding said slidable member. 15. A locker comprising a door, a slidable locking rod for locking the door in closed position, a handle having a groove therein mounted on the front of said door, a slidable member on the door and engaging the rod for operating said rod, and extensions on said slidable member for engaging said groove in the handle and guided thereby. 16. In a locker, a door for said locker, a locking bar carried by the door on the inner face thereof for locking the door in closed position, a hollow handle fastened to the outer face of the door and having a groove therein, a slidable member mounted on the door and cooperating with the bar, said slidable member engageable with said groove for operating the locking bar, and bumpers arranged in said groove and providing strikes for said slidable member. 17. A locker comprising door jambs, a door operably arranged between said jambs and swingingly connected to a said jamb, clips fixed to a face of said door, a hollow sheet metal locking rod having a longitudinal slot therein at the rear face of the rod, said clips extending into said slot for slidably mounting the rod to the inner face of the door, and means on a jamb and cooperating with the rod for locking the door. 18. A locker comprising door jambs, a door operably arranged between said jambs and swingingly mounted on one of said jambs, clips fixed to the inside face of said door, a hollow sheet metal locking rod having a slot therein on its rear face and extending throughout the length of the rod, said clips extending into said slot for slidably mounting the rod to the inner face of the door, means cooperating with the rod for locking the door, and means operable from the outside of the door for operating the slidable rod. 19. A locker comprising door jambs, a door arranged between the jambs, clips mounted on the inside face of the door, a hollow locking rod slidably mounted on the clips and on the inside face of the door, a keeper member fixed to one of said jambs and extending into said rod in the closed position of the door, means for holding the rod in a predetermined position, said means including a member fixed to the door and a member fixed to the rod which members become engaged and hold the rod in unlocked position 70 when the door is in open position, the keeper member disengaging the last two members and releasing the rod when the door is shut. 20. A locker comprising door jambs, a door arranged between the jambs and pivotally attached 75 to a jamb, a slidable locking rod mounted inside of the locker on the door and cooperating with a keeper on a jamb for preventing or permitting opening and closing of the door, means operable from the outside of said locker for raising said rod to unlock the door, means extending inside of the rod for holding the rod in raised position when the first means are operated for unlocking the door, and means controlled by the closing of the door whereby the rod and first named means return to normal position by gravity and the rod will engage the keeper. 21. A locker comprising a door having longitudinal spaced reinforcing members and side flanges, one face of a reinforcing member and a flange providing a pocket, and a hollow locking rod mounted in said pocket on the inner face of the door, said rod being substantially the same size as said pocket. 22. A locker comprising a door having a longitudinal reinforcing member and a flange thereon and providing a pocket between the reinforcing member and the flange, fastening means fixed to said door between a said reinforcing member and the flange, and a hollow locking rod arranged in said pocket and engageable with said fastening means for operably fastening the rod to the door, said rod having openings therein through which the fastening means extend, whereby the fastening means are concealed by the rod when engaged. 23. In a locker having a door, a locking rod for said door, a three-sided pocket in the door for receiving said locking rod, fastening means between two sides of said pocket, said locking rod having openings therein through which the fastening means extend and being engageable with said fastening means, said rod being constructed and arranged to receive and conceal said fastening means when the rod is fastened thereto. 24. A locker comprising a door having spaced longitudinal reinforcing members and providing a three-sided pocket, fastening means arranged in the bottom of the pocket and a hollow locking bar arranged in the pocket and engaging said fastening means and having openings therein through which the fastening means extend, said bar being constructed and arranged to receive and conceal said fastening means when the fastening means are engaged by the locking bar. 25. In a locker, a door for said locker, a locking bar on the door and a keeper on the locker for locking the door in closed position, a hollow handle fixed to the front of the door, a slidable member mounted on the door and engaging the bar for operating said locking bar, the movement of the slidable member being limited by the handle, and lateral extensions on the slidable member and extending into the handle for holding the slidable member in proper operable position and alinement. 26. In a locker, a door for said locker, a locking bar on the door and a keeper on the locker for locking the door in closed position, a hollow handle fixed to the front of the door, a slidable member mounted on the door and engaging the bar for operating said locking bar, the movement of the slidable member being limited by the handle, extensions on the slidable member and extending into the handle for holding the slidable member in proper operable position and alinement, and upper and lower bumpers arranged in the hollow handle and providing strikes for said slidable member.
